UNITED STATES PATENT OFFICE.

ALBERT W. PERSON AND JULIUS E. PERSON, OF HARVARD, NEBRASKA.

ELECTRIC HEATER.

1,212,254.

Specification of Letters Patent. Patented Jan. 16, 1917.

Application filed April 8, 1916. Serial No. 89,917.

To all whom it may concern:

Be it known that we, ALBERT W. PERSON and JULIUS E. PERSON, citizens of the United States, residing at Harvard, in the county of Clay and State of Nebraska, have invented certain new and useful Improvements in Electric Heaters, of which the following is a specification, reference being had to the accompanying drawings.

10 This invention relates to electric heaters, and particularly to that type of heater wherein a series of heating coils are provided extending in parallel relation.

The general object of the invention is the 15 provision of an electric heater built up of a series of units or sections so that heaters of various sizes may be formed by decreasing or increasing the number of units.

A further object of the invention is to so 20 form the units that when placed together, grooves or channels will be formed between any two sections or units, the grooves or channels being of suitable size and shape to receive the heating coils, and still another 25 object in this connection is to provide the sections with surface openings or notches so that when the sections are placed together, openings for the radiation of heat will be provided in the completed element.

30 A still further object is to provide means to secure perfect alinement of the channels and surface openings so that the surface of the heater will be perfectly flat, and the notches which form the openings for the 35 radiation of heat will be kept in perfect alinement, and for this purpose to provide each unit with means for interlocking engagement with the next adjacent unit.

A further object is to provide means at 40 the ends of the units whereby when the units are assembled the wires leading from one set of coils to another set of coils may be arranged so that alternate coils are engaged with each other.

45 A further object is to so construct the units and the completed heating element formed by combining the units that it may be arranged either for single or three-heat wiring, means being provided whereby an

even distribution of heat is obtained either 50 for high, low, or medium heating. By using alternate coils only for medium heat, or coils in series for low heat, and using the coils in two sets, each set being in series and the two sets of coils being in parallel. 55

A further object is to provide heating units and coils which may be readily used in different sizes of heaters by mere duplication of one size of heating section or unit, and in this connection to provide a heater 60 which is particularly adapted for toasters, hot-plates, stoves and ranges, ovens, broilers, grills, etc.

Other objects will appear in the course of 65 the following description.

Our invention is illustrated in the accompanying drawings, wherein:

Figure 1 is a top plan view of a heater constructed in accordance with our invention, part of the heating units being removed; Fig. 2 is a transverse sectional view on the line 2—2 of Fig. 1; Fig. 3 is a sectional view on the line 3—3 of Fig. 1; Fig. 4 is a perspective view of one of the units detached; Fig. 5 is a perspective view of a 75 number of units assembled; Fig. 6 is a top plan view of the unit shown in Fig. 4; Fig. 7 is a section on the line 7—7 of Fig. 6.

Our improved heater, as before stated, is formed of a series of units one of which is 80 illustrated in Fig. 4 and designated 10. Each unit has a relatively wide base 11, a longitudinally extending semi-circular channel 12 above the base and on each side of the medium web of the unit, and a relatively 85 top flange 13 having the same length as the base and the same width as the base but being cut out or notched at a plurality of points, as at 14, the edge walls of the notches being beveled and the notches being relatively long. At the ends, each unit is formed with an outwardly projecting lug 15. All of the units are of the same character, except the end units 10^a, in which the channel 12 and the notches 14 are only provided on one 95 side face and the lug 15 is relatively large.

It will be seen that each unit as heretofore described comprises a bar of non-con-

ducting material formed to provide a base 11 from which extends an upwardly projecting rib 13 which is tapered toward its upper edge, this rib being provided adjacent 5 its upper edge and on each side of the rib with outwardly extending ribs defined by the material and separating the notches 14, these lugs extending outward so that the outer faces of the lugs are in the same plane 10 as the edge faces of the base 11 and that when the units are placed together as in Fig. 2, the units provide a relatively solid reflecting surface below the coils with heat radiating openings above the coils so that 15 all the heat of the coils is reflected upward or through the heat radiating openings. It is further pointed out that by forming the units with interlocking tenons and recesses the units cannot shift longitudinally or vertically 20 upon each other but that the units serve to support each other and there is no chance for the units becoming displaced.

It will be seen from Fig. 5 that when the units are placed together side by side with 25 the edge faces of the bases in contact with each other, the channels 12 will coact with each other to provide a longitudinally extending chamber while the notches 14 will coact to provide a series of longitudinally 30 extending slots or radiation openings which open into the channels 12. There will thus be provided without regard to the face of the heating element, a sectional slab having a series of bores or chambers extending 35 longitudinally through it, spaced from each other, with a series of slots or radiation openings extending down into these bores, and the ends of this slab will be provided with a plurality of outwardly projecting 40 lugs 15 disposed one between each pair of bores or channels. These units 10 are to be made of porcelain or other like non-conductive material.

The several units 10 which together form 45 the completed slab or heating element may be connected to each other and held together in any suitable manner, as for instance, by a frame, surrounding and supporting the several elements. One form of this support 50 for the heating elements will be described later. Disposed within the channels formed by the grooves 12 are a plurality of heating coils 16 of any usual or suitable character, these coils as illustrated in Fig. 1 being disposed beneath the openings formed by the notches 14. In order to provide for securing 55 a medium, a low, and a high heat, it is necessary that the several coils should be connected to each other, as indicated in 60 Fig. 1.

For the purpose of distinguishing between the several coils I designate one set of coils as *a*, and another set as *b*, and from Fig. 3 it will be seen that one coil *a* is connected

by a wire 17 which passes over two of the 65 lugs 15 to the next adjacent coil belonging to the *a* series, while the coils *b* are connected by wires 17 which pass beneath the lugs 15. At one end of the heating elements are the binding screws 18 and 19, the binding screw 70 18 engaging with the first coil *a* while the binding screw 19 engages with the first coil *b* of the series of coils *a* and *b*. A switch *A* is provided having a binding screw 20 from which a conductor wire or other suitable conductor passes to the binding screw 18 while the binding screw 21 of the switch is connected by means of a wire or other suitable conductor to the binding screw 19. 75

At the opposite corner of the slab formed 80 of the series of sections there is a binding screw 22 to which the last coil of the series *b* is connected and to which the last coil of the series *a* is connected, and from this screw 22 extends a wire 23 which extends 85 to the binding screw 24 on the switch. Wires 25 and 26 lead to a source of current, the wire 25 being engaged with the binding screw 27 while the wire 26 is connected to the binding screw 21. Switch arms are provided, whereby the wire 25 may be electrically connected either to the binding post 24 or to the binding post 20, or whereby the post 21 may be connected to the post 24 or disconnected therefrom. By this means the 90 coils may be placed either in series or alternate coils may be placed in parallel with each other, or only one set of coils may be heated. This form of switch is of a well known type hence requires no specific description of the construction.

In order to hold these sections or units to each other in order to secure perfect alignment of the grooves and surface openings, we have provided recesses that dowel or fit 105 into each other so as to interlock one unit with another. These recesses in the side faces of the units are designated 29, while the projections or dowels are designated 30. These recesses are preferably triangular in 110 cross section and have inwardly converging side walls, while the projections or dowels are formed to fit these recesses and side walls. By this means we secure the perfect alignment of the sections so that the upper 115 face of the slab so formed will be perfectly flat and the notches 14 of the sections which form the openings for the radiation of heat in the completed element of the slab will be kept in perfect alignment. Under these circumstances this heater or slab formed of sections as before described, should be used 120 in connection with a sub-base which is designated 31 and illustrated in Fig. 2. This sub-base is made of a composition which 125 resists the passage of heat by conductance, and of such material that it will endure temperatures sufficiently high for all practi-

cal purposes. As illustrated, this sub-base is rectangular in form and the side walls are formed to provide a ledge 32 upon which the ends of the sections rest, this ledge extending entirely around the sub-base, thus providing a dead air space 33 below the slab formed of the sections 10. When the heating element formed of the sections is intended to be used in a toaster, oven, grill or broiler, it is used without the sub-base, the sections or units of the element being clamped together in any suitable manner. When, however, it is used for a hot-plate, range or like structure, then the sub-base is to be used.

It is evident that a heating element constructed in accordance with this invention has all the advantages of the open coil type of heater with the additional advantage of offering protection to the heating coils as they are held firmly in place and to a large extent housed. The completed slab or heating element is easy to build, and the size of the slab or element may be varied even where only one size of section or unit is used by varying the number of sections that go into the element. Provision is made by the use of the lug 15 whereby the heating coil may be alternated without loss of efficiency. It is of course obvious that the heating element may be used in any position, and this is a great advantage in ovens and broilers where it is desirable to use the heating element in an inverted position. It is not necessary in this element to fasten the heating coils to the insulating base, that is, to the slab, by screws, nails, or other means, as the heating coils are held firmly in place by the sections themselves. Even distribution of heat is obtained for high, low, or medium heats, by operating the switch so that alternate coils only are used on medium heat, all the coils in series on low heat, and two sets of half the coils, the coils of each set being in series, on a high heat, the coils of one series being in parallel to the coils of the other series.

While we have illustrated certain details of construction and arrangement of parts which have been found most effective in practice, we do not wish to be limited to these details or arrangements as it is obvious that many changes might be made without departing from the spirit of the invention.

Having described the invention, what is claimed is:

1. An electric heating element comprising a plurality of conjoined units of non-conducting material having interlocking engagement with each other, and formed to provide coil receiving channels.

2. An electric heating element comprising a plurality of conjoined units of non-conducting material, each unit having longitudi-

dinal grooves disposed on its opposite faces which, when the units are conjoined, provide longitudinally extending coil channels.

3. An electrical heating element comprising a series of conjoined units, each unit having oppositely disposed longitudinally extending grooves in its opposite faces which, when the units are conjoined, provide longitudinally extending coil channels, and each unit having notches on its side faces intersecting the grooves, which, when the units are conjoined, provide heat radiation openings.

4. An electrical heating element comprising a series of conjoined units, each unit having oppositely disposed longitudinally extending grooves in its opposite faces which, when the units are conjoined, provide longitudinally extending coil channels, and each unit having notches on its side faces intersecting the grooves, which, when the units are conjoined, provide heat radiation openings, each element being provided with a plurality of recesses and having corresponding projecting dowels which when the units are conjoined engage with the recesses to thereby hold the units in alignment.

5. An electrical heating element comprising a plurality of conjoined units, each unit having oppositely disposed grooves in its faces which when the units are conjoined provide longitudinally extending coil channels and each unit being provided on its ends with projecting non-conducting conductor supporting lugs smaller in cross section than the cross section of the units.

6. An electrical heating element comprising a plurality of conjoined units of non-conducting material, each unit having oppositely disposed longitudinal grooves in its side faces which when the units are conjoined provide longitudinally extending coil channels, each unit having notches on its side faces intersecting the grooves which when the units are conjoined provide radiation openings, each unit being formed on one side face with recesses and on the opposite side face with projecting dowels corresponding to the recesses which when the units are conjoined engage with each other to thereby hold the units in alignment, and each unit at its ends being formed with projecting lugs smaller in cross section than the cross section of the units.

7. A unit for electrical heating elements formed of an elongated block of non-conducting material, the side faces of the block being formed with longitudinally extending grooves whereby when a plurality of the units are conjoined coil channels shall be provided, the side faces of each unit being formed with vertically extending notches intersecting the coil channels to form radiation.

openings when a plurality of units are conjoined.

8. A heating element of non-conducting material having a plurality of coil channels extending through it in parallel relation, the end faces of the heating element being provided with outwardly projecting lugs disposed between the coil channels, heating coils disposed in the coil channels, alternate coils being connected alternately at opposite ends of the heating element by wires passing on one side of said lugs, the other coils being connected at opposite ends by wires passing on the other side of said lugs, means whereby by one coil of each set of coils may be connected to a source of current and a return conductor common to both sets of coils, and means whereby current may be directed into all of said coils in series or into the sets of 20 coils in parallel.

9. A unit for electrical heating elements comprising a solid bar of non-conducting material having longitudinal grooves on opposite side faces whereby when two of said 25 units are conjoined the grooves shall define a longitudinally extending coil channel.

10. A unit for electrical heating elements comprising a solid bar of non-conducting material having longitudinal grooves on opposite side faces, said grooves extending from end to end and opening upon the end faces of the bar whereby when a plurality of 30 units are conjoined the grooves will define a plurality of longitudinally extending coil channels opening upon the end faces of the 35 element so formed.

11. A unit for electrical heating elements comprising a solid bar of non-conducting material having longitudinal grooves on opposite side faces whereby when a plurality of 40 units are conjoined the grooves will define a plurality of longitudinally extending coil channels, said bar at its ends being formed with projecting integral lugs spaced from 45 the faces of the bar.

12. A unit for electrical heating elements comprising a solid bar of non-conducting material having longitudinal grooves on opposite side faces whereby when a plurality of 50 units are conjoined the grooves will define a plurality of longitudinally extending coil channels, the bar being formed upon the grooved faces with means whereby it may be interlocked with an adjacent bar.

13. A unit for electrical heating elements comprising a solid bar of non-conducting material having longitudinal grooves on opposite side faces whereby when a plurality of 60 units are conjoined the grooves will define a plurality of longitudinally extending coil channels, the bar being formed upon one of its grooved faces with recesses and on the opposite grooved face with projections disposed in alinement with said recesses whereby the

bars when placed together may be interlocked from movement in the plane of said grooved faces.

14. A unit for electrical heating elements comprising a solid bar of non-conducting material, said bar having a relatively wide base, a medially disposed rib extending approximately at right angles from the base, and lugs extending out at spaced intervals from said rib on opposite faces thereof and spaced from the base, the outer end faces of 75 said lugs being in the same plane as the edge face of the base.

15. A unit for electrical heating elements comprising a solid bar of non-conducting material, said bar having a relatively wide base, a medially disposed rib extending at right angles from the base and tapering transversely from the base, and integral lugs extending out at spaced intervals from the rib on opposite faces thereof and spaced from 85 the base, the end faces of the lugs and the edge face of the base being in the same plane.

16. A unit for electrical heating elements comprising a solid bar of non-conducting material, said bar having a relatively wide base, a medially disposed rib extending at right angles from the base and tapering transversely from the base, and integral lugs extending out at spaced intervals from the rib on opposite faces thereof and spaced from 95 the base, the end faces of the lugs and the edge face of the base being in the same plane, one edge face of the base being formed with recesses and the opposite edge face with projections disposed in alinement with the recesses.

17. An electrical heating element formed of a plurality of units of non-conducting material, the units being formed to provide a plurality of longitudinally extending coil 105 channels through the heating element and provide heat radiating openings extending from one face of the element into and intersecting said coil channels, said units abutting against each other to prevent the radiation 110 of heat except through said heat radiating openings.

18. The combination with an electrical heating element comprising a series of conjoined units and heating coils inclosed in 115 said units, of a base of non-conducting material having a recess in which the units are disposed, said recess being square and having an area equal to the area of the heating element formed by the conjoined units to 120 thereby hold the units in engagement with each other, the recess being formed with a shoulder upon which the margin of the heating element rests to thereby provide a dead air space below the heating element.

19. A heating element of non-conducting material having a series of coil channels extending through it in parallel relation, the

end faces of the heating element being provided with outwardly projecting lugs disposed between the coil channels, said lugs being less in thickness than the thickness of
5 the heating element and having a width not greater than the distance between the adjacent walls of adjacent coil channels.
In testimony whereof we hereunto affix

our signatures in the presence of two witnesses.
